UNITED STATES PATENT OFFICE.

JOSEPH H. COYNE, OF NEW YORK, N. Y., ASSIGNOR TO HIMSELF AND
MICHAEL A. BURDETTE, OF SAME PLACE.

IMPROVEMENT IN SINKS.

Specification forming part of Letters Patent No. 133,414, dated November 26, 1872.

To all whom it may concern:

Be it known that I, JOSEPH H. COYNE, of the city and State of New York, have invented an Improvement in Sinks, of which the following is a specification:

The vapors and effluvia escaping into apartments from sinks are fruitful sources of sickness, and, in consequence of the siphon action in the trap usually employed, there is great difficulty in preventing the escape of these noxious gases. This difficulty is increased in houses where sinks are numerous, the apartments small and badly ventilated, and the occupants numerous.

My invention is made for closing the escape sink-pipe to prevent vapors or gases escaping from the sewer-pipe, and also for retaining water when desired in the sink for washing purposes.

I make use of a movable valve above the grating to cover the same and close the holes leading to the sewer-pipe, thereby preventing the escape of vapors or smell or retaining water in the sink, and my device can be applied to sinks already constructed and in use.

In the drawing, Figure 1 is a plan of my valve applied to a sink, and Fig. 2 is a vertical section of the same.

The sink *a* is of any usual character, and provided with the strainer or grating *b* covering the end of the sewer-pipe *c*. The valve *d* is made with a flexible or elastic face, of rubber, leather, or similar material, and with a knob or handle, *e*, by means of which it is to be moved so as to cover or uncover the strainer *b*. I prefer to attach this valve by an arm and screw or rivet, *i*, so that it can be swung over the strainer or away from the same; hence, with sinks that are already in use this valve can be attached by boring a hole through the bottom and inserting a shouldered bolt with putty, and screwing upon the lower end the nut. In cases where the sink is to be constructed with reference to receiving this valve there may be ribs upon the surface, between which the valve may be slid.

I claim as my invention—

The removable valve *d* applied to and combined with the strainer or grating of a sink, substantially as and for the purposes set forth.

Signed by me this 4th day of October, A.D. 1872.

JOSEPH HENRY COYNE.
